MACHINE FOR TREATING SKEINS OF TEXTILE MATERIAL

Léon Ganeval, Lyon, France

Application December 3, 1931, Serial No. 578,838
In France December 11, 1930

8 Claims. (Cl. 28—58)

My invention relates to a machine for treating skeins of textile material. This machine performs in a single operation several treatments which have hitherto been performed separately, 5 viz, centrifuging the skeins, rendering them supple, beating and drying them.

This machine comprises a housing within which is disposed a circular rotating support, the skeins being radially arranged on said support and the latter being provided with means whereby the skeins are driven as a belt on its pulleys, and also with means to suddenly strike them.

In the annexed drawings:

Fig. 1 is a front view of the machine, with partial section of the front cover.

Fig. 2 is a section of Fig. 1 along line II—III.

Fig. 3 is a back view of the machine, with partial section of the end cover.

The machine comprises a frame 1 supporting 20 the driving motor 2. The latter drives a worm 3 cooperating with a worm wheel 4 keyed on the main shaft 5. Shaft 5 is supported by ball bearings 6. 7 designates a gear box integral with frame 1. The front end of shaft 5 projects from 25 box 7 and it is provided with a circular plate 8 of large diameter.

Plate 8 is provided with two circular ranges of skein rollers. The rollers of the first range are located near the plate center. They are freely 30 rotatable within the corresponding bores of plate 8 and they support pulleys 10 behind said plate, each roller being associated with one pulley 10, one roller of the range having also a second pulley 11 (Fig. 2) adjacent to its individual pulley 10.

Pulleys 10 are connected together by means of 35 an endless belt 12 (Fig. 3), and pulley 11 cooperates with a belt 13 which is passed in a groove 14 provided in a hub 15 loose on shaft 5.

Hub 15 is passed through the front end wall 16 40 of box 7 and it is provided, within said box, with a pinion 17. Shaft 5 is also provided with a pinion 18 and pinions 17 and 18 are connected together through a secondary shaft 19 provided with pinions 20 and 21.

The rollers 22 of the second range are located 45 near the rim of plate 8. They are equal in number to rollers 9. And they are loose on shafts 23 eccentrically supported by plates 24 keyed on shafts 25, the latter being loose within bores of plate 8 behind which they are provided with radial tails 26 terminating into fingers 27.

Plate 8 may be braked by friction members 28 supported by a shaft 29 having right and left hand threads, said shaft being controlled through 50 a lever 30. The rotation of shaft 29 axially moves

members 28 (which are threaded as nuts) and presses them against the rim of plate 8.

As shown, Fig. 2, pinion 21 is loose on shaft 19 and a clutch device 31, operated by a lever 32, is provided to control the rotation of hub 15. 60

At the lower part of frame 1 there is arranged an inclined abutment 43 keyed on a shaft 33 actuated by a lever 34 locked at any desired position by means of an indented sector 35. This member 43 may cooperate with tails 26 during the rotation 65 of plate 8.

The latter and rollers 9 and 22 are housed within in a box 44 having a central inlet 36 and a tangential outlet 37. A door 38 is provided for loading and unloading the machine. Heating 70 radiators 39 are disposed near the inlet. They are preferably arranged within a perforated cylinder 45 as shown, Fig. 2. The machine operates as follows:

The skeins are disposed between a roller 9 and a 75 roller 22, the arrangement being preferably radial. Motor 2 is then started. Rollers 22 are thus submitted to a centrifugal action, whereby the skeins are tensioned.

Pinion 21 is then clutched. Pinions 17 and 18 80 being somewhat different in diameter, hub 15 rotates at a speed different from the speed of plate 8. Thus pulley 11 and rollers 9 are rotated at low speed. The skeins are driven around rollers 9 and 22 as a belt around its pulleys.

Tails 26 strike abutment 43 and are thus rotated around their individual axles against centrifugal force. The skeins are momentarily relieved from tension. When a tail 26 escapes from abutment 43, the corresponding roller 22 resumes 85 its former position whereby a blow is given to the skeins.

The latter act as the vanes of a centrifugal fan and air is rapidly circulated from 36 to 37. The skeins are thus rapidly dried. A part of the 90 heated (and not wholly saturated) air may be used again as it is well known in the drying industry. 40 designates the pipe for heated air, 41 being an adjustable valve of any description.

42 in Figs. 2 and 3 designates stops to limit the 95 angular motion of plates 24.

The machine thus performs the following operations: centrifuging the skeins, making them supple, beating them and drying them by preferably heated air. It comprises no tensioning screws or the like to be operated during loading. The blow given by a roller 22 to the skeins is independent of their length or weight which is of 105 importance since the dry skeins are different in weight and often in length from the wet ones.

I claim:

1. A machine for treating skeins of textile material subsequently as described, comprising in combination a rotating support; a first range of 5 rollers rotatably supported by said support, said rollers having their axles parallel to the support axis; means to rotate said rollers; a second range of rotatable rollers located exterior to said first range and substantially in radial alignment therewith, said rollers being equal in number to those of said first range and having also their axles parallel to the axis of said support; and individual supports for the axles of said second-named rollers, said individual supports being 10 movably supported by said rotating support in such a way that any one of said second-named rollers may be freely moved towards the periphery of said support under centrifugal action, its axis being always parallel to the rotating support 15 axis.
2. A machine as claimed in claim 1, comprising an adjustable abutment in the path of the individual supports of the rollers of the second range, said abutment being adapted to move said supports towards the axis in succession against centrifugal action and to suddenly free them.
3. A machine as claimed in claim 1, wherein the individual supports for the rollers of the second range are in the form of plates rotatably supported by the general rotating support, the roller axis being eccentrically fixed thereon, each one of 20 said plates being connected with an actuating tail adapted to be actuated by the adjustable abutment.
4. An apparatus for centrifugally drying, stretching and beating skeins of textile material comprising a rotary shaft, a plurality of rotatable skein supports carried by and concentrically positioned about said shaft, a plurality of movable skein supports carried by and positioned about 25 said shaft, said movable supports being substantially radially aligned with the rotatable supports, said movable supports being freely movable about their supporting axes and being adapted to be urged in a direction substantially radially from said shaft by centrifugal force produced by rotation of the shaft and the skein supports carried thereby.
5. An apparatus for centrifugally drying, 30 stretching and beating skeins of textile material comprising a rotary shaft, a plurality of rotatable skein supports carried by and concentrically positioned about said shaft, a plurality of movable skein supports carried by and positioned about said shaft, said movable supports being substantially radially aligned with the rotatable supports, said movable supports being freely movable about their supporting axes and being adapted to be urged in a direction substantially radially from 35 said shaft by centrifugal force produced by rotation of the shaft and the skein supports carried thereby.
6. An apparatus for centrifugally drying, stretching and beating skeins of textile material comprising a rotary shaft, a plurality of rotatable skein supports carried by and concentrically positioned about said shaft, a plurality of movable skein supports carried by and positioned about 40 said shaft, said movable supports being substantially radially aligned with the rotatable supports, said movable supports being freely movable about their supporting axes and being adapted to be urged in a direction substantially radially from said shaft by centrifugal force produced by rotation of the shaft and the skein supports carried thereby, an element adapted to be placed 45 in the path of rotation of the movable supports to which path the movable supports are urged by centrifugal force for moving the movable supports out of said path in a direction toward the shaft against centrifugal force.
7. An apparatus for centrifugally drying, stretching and beating skeins of textile material comprising a rotary shaft, a plurality of rotatable skein supports carried by and concentrically positioned about said shaft, a plurality of stub shafts carried by and positioned about the shaft 50 in substantially radial alignment with the rotatable skein supports, movable skein supports eccentrically carried by the stub shafts and adapted to be urged substantially radially away from said rotary shaft by centrifugal force, and means for periodically rocking the stub shafts to cause the movable supports to move toward the rotary shaft against centrifugal force.
8. An apparatus for centrifugally drying, stretching and beating skeins of textile material comprising a rotary shaft, a plurality of rotatable skein supports carried by and concentrically positioned about said shaft, a plurality of stub shafts carried by and positioned about the shaft 55 in substantially radial alignment with the rotatable skein supports, movable skein supports eccentrically carried by the stub shafts and adapted to be urged substantially radially away from said shaft by centrifugal force, an arm on each of the stub shafts, and means for moving a cam into the circular path of travel of said arms to effect rotation of the stub shafts and thereby vary the distance between pairs of substantially radially spaced skein supports.

LÉON GANEVAL.
